(57) **CLAIM**

We claim the ornamental design for a gold pan, as shown and described.

DESCRIPTION

FIG. 1 is a perspective view of a gold pan, showing our new design with a grate thereof in a lowered position;

FIG. 2 is a perspective view thereof, illustrated with the grate in a raised position;

FIG. 3 is a left-side elevational view of FIG. 1, the right-side elevational view being a mirror image thereof;

FIG. 4 is a front elevational view of FIG. 1, the rear elevational view being a mirror image thereof;

FIG. 5 is a top plan view of FIG. 1; and,

FIG. 6 is a bottom plan view of FIG. 1.
